(57) **CLAIM**

The ornamental design for an electricity distribution box, as shown and described.

DESCRIPTION

FIG. 1 is a front right perspective view of an electricity distribution box showing our new design;

FIG. 2 is a front view of the design shown in FIG. 1;

FIG. 3 is a right side view of the design shown in FIG. 1, the left side view being the same;

FIG. 4 is a rear view of the design shown in FIG. 1;

FIG. 5 is a bottom view of the design shown in FIG. 1; and,

FIG. 6 is a top view of the design shown in FIG. 1.

The broken lines shown in the figures are included for the purpose of illustrating portions of the electricity distribution box and form no part of the claimed design.
